TOILET POWDER DISPENSING DEVICE

Daniel Topjian, Watertown, Mass., assignor, by
mesne assignments, to himself, as trustee

Application June 27, 1942, Serial No. 448,747

10 Claims. (Cl. 15—227)

This invention pertains to toilet powder dispensing devices, in particular to a powder-applying mitt such as is employed for dusting large areas of the body with toilet powder, the present invention being an improvement upon the device disclosed in my Patent No. 2,233,686, dated March 4, 1941.

As pointed out in my prior patent, the quantity of powder used for dusting the entire body, for example after taking a bath, is quite substantial as compared with that used in powdering the face only; the hand of the user must assume awkward and difficult positions in applying powder to certain areas of the body; and, unless special precautions be taken in the design of the powder-applying device, much powder will be scattered about, causing waste and untidiness in the surroundings. Furthermore, since as above noted the amount of powder used at each application may be comparatively large, the supply of powder in the applying device is quickly depleted and unless the device be so designed as to permit it to be refilled, it must soon be discarded, even though structurally capable of much longer use.

Even though it might be possible, by ripping seams or the like, to introduce powder into dispensing devices not designed for refilling, such a possibility is of no real practical value since the average user of such an article has neither the time nor the inclination to do such work. In consequence it is requisite, as a practical matter, so to design the dispensing device as to permit it to be refilled easily and quickly and as frequently as may be desired and without the exercise of undue care to prevent spilling and waste. It is even more important that when the device is supplied with powder and in use, the powder shall not escape readily through the filling opening.

In my aforesaid patent the dispensing device, in the form of a mitt, has a dispensing surface substantially as large as the hand and is provided with a filling opening at its wrist portion, such filling opening being normally closed by a flap held in closing position by separable fasteners, for instance a plurality of snap fasteners. While the arrangement disclosed in said patent is desirable and wholly adequate for the purpose and of great commercial value, the present defense program makes it difficult to obtain separable fasteners of any kind in sufficient quantity for the manufacture of such dispensing devices on a large scale. Accordingly, the present invention has for its principal object the provision of a

5 refillable toilet powder dispensing mitt of the type disclosed in my aforesaid patent but comprising improved closing means for the filling opening such that the number of fasteners employed may be diminished (as compared with the arrangement disclosed in the patent) or the separable fasteners may be completely dispensed with but at the same time with assurance of as good or even better and more secure retention of the 10 powder when the filling opening is closed than in the patented construction. A further object of the present invention is to provide a novel and useful method of assembling the constituent parts of and completing the improved dispensing 15 device.

Other and further objects and advantages of the invention will be pointed out hereinafter in the following more detailed description and by reference to the annexed drawings wherein

20 Fig. 1 is a front elevation with certain parts broken away, illustrating a preferred embodiment of the present invention and indicating the relative position of the parts during filling;

Fig. 2 is an edge elevation, partly in section, 25 on the line 2—2 of Fig. 1, but showing the mitt in inverted position;

Fig. 3 is a fragmentary section, on a plane similar to that of the sectioned part of Fig. 2, illustrating a modified construction;

30 Figs. 4, 5, 6 and 7 are diagrammatic plan views, to smaller scale, illustrating blanks useful in making the mitt illustrated in Fig. 3;

Figs. 8, 9, 10 and 11 are plan views of blanks 35 useful in making the preferred form of mitt shown in Fig. 1, Figs. 10 and 11 being to smaller scale than Figs. 8 and 9, Fig. 8 illustrating the step of attaching a finish bead to one end of the blank;

Fig. 12 is a perspective view illustrating a resilient stiffener strip preferably employed in the preferred construction;

Fig. 13 is a fragmentary transverse section 40 showing the wrist portion of the liner member 45 of the mitt;

Fig. 14 is a perspective view of the liner member separate from the other parts;

Fig. 15 is a fragmentary longitudinal section 50 through the wrist portion of the palm member of the mitt, showing the first step in assembling this part with a closure member;

Fig. 16 is a perspective view of the closure member before assembly with the palm member;

Fig. 17 is a fragmentary longitudinal section

showing a later step in the assembly of the palm member and closure member;

Fig. 13 is a fragmentary longitudinal section similar to that of Fig. 2, but to larger scale, showing the closure means for the powder-receiving pocket in operative assembly;

Fig. 19 is a fragmentary plan view of the back blank before folding, showing an elastic strip to the blank;

Fig. 20 is a front elevation showing the mitt at the completion of the side seams which unite its several plies; and

Fig. 21 is a fragmentary elevation, partly broken away and partly in vertical section, showing the liner member with its inner valve flap and indicating the funnel shaped entrance to the powder-receiving pocket.

Referring to the drawings, the character M indicates the improved mitt of the present invention in a preferred embodiment, the mitt comprising the hand portion H, the fingertip portion F, and the wrist portion W. The mitt comprises three layers of flexible material of generally similar contour and arranged in registry with each other and permanently united along the lateral edges of the mitt and around the fingertip portion of the mitt, the several layers being free from each other at the wrist portion of the mitt. The front layer 1 (Fig. 2) consists of some powder-pervious material, such for example as Turkish toweling or terry cloth, while the intermediate layer 2, which is hereinafter referred to as the "liner" consists of some material which is substantially impervious to powder, for example a closely woven textile fabric or a textile or other fabric impregnated with some material, for example size, a rubber compound, a synthetic resin or the like, which closes its pores and while leaving it flexible prevents the passage of powder through its interstices. The rear layer or back 3 of the mitt preferably comprises two layers or plies 3^a and 3^b of some suitable fabric, preferably ornamental, for example figured taffeta or the like, although any other suitable material may be employed. The several layers which thus make up the mitt are of such shape and dimensions that the powder-applying member 1 is of an area approximately as large as that of the hand upon which the mitt is worn, the powder-receiving pocket 4 which is defined by the palm member 1 and the liner 2 being of capacity sufficient to hold a substantial quantity of powder so that although the mitt be employed for dusting large areas of the body, the powder-receiving pocket need not be replenished with undue frequency. The hand-receiving pocket 5 has substantially as great a superficial area of the powder-receiving pocket, so that, when the mitt is used, the hand forms a backing for the entire body of powder in the pocket 4 and thus permits the user to conform the body of powder and the powder-applying palm member 1 to the surfaces of the body by properly flexing the thumb and fingers.

Fig. 8 is a diagrammatic plan view of a blank 3^x suitable for forming the back 3 of the mitt, this blank 3^x as illustrated having substantially parallel lateral edges and curved ends 3^m, and a transverse fold line 10 substantially midway between its ends. This blank, as above suggested, may be of any desired material, preferably a fabric of dainty or ornamental character such for example as a taffeta or the like, and is doubled along the transverse fold line 10 so that the back 3 of the mitt is two-ply or of double

thickness, the fold at 10 defining the free edge 7 (Fig. 2) of this back member at the wrist. In thus folding the blank 3^x, its wrong side is exposed.

In Fig. 9 there is illustrated the blank 1^x which forms the palm of the mitt. This blank is in shape and dimensions substantially like either half of the blank 3^x except that it is slightly longer, and has the fold line 11 adjacent to its straight end 11^a. This blank is made of some powder-pervious material, for example Turkish toweling or terry cloth of sufficiently loose weave to permit the powder to sift through it over its entire area. Material such as Turkish toweling or terry cloth has the added advantage that it provides a soft surface useful in spreading the powder. Obviously other materials having the requisite powder permeability may be used if desired.

In Fig. 10 there is illustrated, to smaller scale, a blank 2^x for use in forming the liner or intermediate layer of the mitt. This blank 2^x has the rounded end 2^m, similar to the rounded end 3^m of the blank 3^x, and between this end and a transverse fold line 12 is substantially of the same size and dimensions as either half of the blank 3^x. The blank 2^x extends beyond the fold line 12 and is provided with transverse fold lines 13, 14 and 15, the fold line 15 being spaced from the straight end of the blank substantially the same distance that the fold line 11 is spaced from the straight edge 11^a of the blank 1^x.

In Fig. 11 a blank 16 is illustrated, to small scale, which is useful in association with the other blanks in forming closure means for the open end of the powder-receiving pocket. This blank 16 is substantially rectangular and may be made of any suitable flexible fabric, for example a closely woven textile material like the liner. It is substantially rectangular in contour and has the transverse fold lines 17, 18 and 19.

A further element S of the preferred embodiment of the invention is shown in Fig. 12, this element S being a narrow elongate strip of some stiffly resilient material, for example Celluloid, synthetic resin, cardboard, or textile fabric impregnated with some substance such as to impart stiffness and a certain degree of resiliency.

In assembling the several parts which form the mitt, the blank 2^x may first be folded along the fold line 13 and then the resultant plies permanently stitched together at 2^a (Fig. 13) substantially where the lines 12 and 14 register with each other thus forming the two-ply hem 22. The plies may also preferably be stitched together by a transverse seam at the point 2^c (Fig. 13). At a subsequent point in the assembly operation, the material intervening between the seam 2^a and the fold line 13 is bent back upon itself as shown in Fig. 13, substantially along the fold lines 12 and 14, so that the hem 22 is parallel to but slightly spaced from the body of the blank. The hem 22 is designed to receive one of the stiffener strips S (Fig. 15). Likewise at a later stage in the assembly, the upper plies 21 (Fig. 13) of the folded blank 2^x is folded along the line 15 so that its end portion or valve flap 21^x is substantially parallel to but slightly spaced from the part 21 to form the narrow channel 21^m.

The blanks 16 and 1^x are now assembled (Fig. 15), the blank 16 being first folded transversely along the lines 17 and 18 (Fig. 16) thus providing the deep valve-flap 20 which is so disposed upon the blank 1^x that the edge 16^a of the blank 16

registers with the straight edge 11^a of the blank 1^x . The blanks 16 and 1^x are now permanently secured by a seam 16^m (Fig. 15) and then the blanks are folded over, as shown in Fig. 17, so that the fold defines the free edge 9 of the palm member at the wrist portion. The folded over blank 16 is then permanently secured to the blank 1^x by a seam at 16^x passing through fold 18 , thereby defining the hem 24 which is designed to receive one of the stiffener strips S and whose free edge 17 is spaced from the edge 9 to define the narrow channel 23 .

In the assembled mitt the free edge 20^x of the valve flap 20 of the blank 16 is disposed within the narrow channel 21^m of the deep valve flap 21 , while at the same time the hem 22 seats within the narrow channel 23 . With the parts thus arranged, the deep valve flaps 20 and 21 are preferably united by the converging seams 26 and 27 (Fig. 21), said seams being widely apart near the wrist end of the mitt and converging toward each other to define between them a funnel-like entrance passage 28 between the valve flaps 20 and 21 through which the powder may be introduced into the powder pocket. After these seams 26 and 27 have been formed the stiffener strips S , if the latter be used, are slipped into the hems 22 and 24 respectively, and after placing the palm and liner blanks in registry, with the hem 22 in the channel 23 , the blanks are united at their wrist portions by seams which close the ends of hems 22 and 24 .

Preferably the edges of the mitt are finished with an ornamental tape, preferably comprising a bead portion 6 , which may be of substantially circular cross section, and an attaching flap 6^b . This finish tape is stitched around one end portion of the back blank 3^x , extending from the fold line 10 along one edge, then around the curved end 3^m , and then up along the other straight edge to the fold line, the tape being secured to the right side of this blank with its bead edge 6 disposed inwardly from the edge of the blank. If desired, a strip 29 of elastic material is arranged transversely across the blank 3^x substantially at the junction of the wrist and hand portions, and is stitched to the wrong side of this same end of the back blank.

The back blank 3^x is now folded wrong side out along the fold line 10 and slipped over the wrist ends 9 and 8 of the assembled palm and liner blanks and registered with the latter. The several plies of material are now stitched, preferably by simple seams, beginning at the wrist and extending down along each side of the mitt to the points A (Fig. 20), leaving the plies unconnected between the points $A-A$.

The mitt is now turned by drawing the wrist portion down through the open tip portion so as to cause the two plies 3^a and 3^b of the back blank 3^x to lie in contact with their wrong sides opposed to each other. The mitt is then again turned wrong side out by pulling the tip portion upwardly through the hand-receiving pocket and out at the wrist, and the several plies, including the bead member, are sewed together by a through-and-through seam around the tip from one point A to the other point A . The mitt is then again turned inside out by drawing the tip portion of the mitt through the hand pocket, thus leaving the mitt right side out and complete.

When the mitt is complete the two hems 22 and 24 with their included stiffeners form stiff shape-retaining members which for convenience will hereinafter be referred to as "shutters,"

which resiliently resist deformation although they may be flexed (Fig. 1) at their central portions so as to provide between them an opening for the introduction of powder. It will be noted that these shutters are permanently united at their opposite ends by the seams which close the ends of the hems, that the outer edge of the shutter 22 is permanently united to the liner member by the transverse seam 2^a ; that the inner edge of the shutter 24 is permanently united to the palm member by the transverse seam 16^x ; and that thus only the inner edge 13 of the shutter 22 and the outer edge 17 of the shutter 24 is free, the edge 13 normally being disposed within the channel 23 and in contact with the inner surface of the shutter 24 . At the same time the edge 20^x of the inner valve flap 20 is disposed in the narrow channel 21^m of the deep valve flap 21 .

Assuming that the powder pocket 4 contains powder, it will be noted that if the mitt be held in inverted position, as illustrated in Fig. 2, the only way that the powder can escape is by first forcing its way up beneath the edge of the member 21^x and between the valve flaps 20 and 21 , and then inwardly over the edge 17 of the stiff shutter 24 into the channel 23 , then around the inner edge 13 of the stiff shutter 22 and out between the latter shutter and the outer wall of the channel 23 . It is thus substantially impossible for powder to escape accidentally after once being introduced into the mitt, the shape of the filling funnel 28 also contributing to such retention of the powder in the pocket. Thus no matter in what position the glove may be used there is substantially no danger that powder will be spilled.

For filling the powder pocket the edge 13 of the shutter 22 is pulled out of the channel 23 and flexed upwardly, as illustrated in Fig. 1, so as to give admission to the wider end of the funnel 28 . The weight of the powder entering the channel tends to force the edge 20^x of the flap 20 out of the channel 21^m , such action being facilitated if desired by transversely compressing the mitt. The powder thus passes through the funnel 28 , past the edge 20^x of the flap 20 and into the pocket. When the powder has all entered the pocket and the mitt is laterally distended to normal shape, the edge 20^x tends to resume its normal position within channel 21^m and the shutter 22 , when released, tends to straighten and to reenter the channel 23 , the inherent resiliency of the shutters 22 and 24 , as well as the normal tendency of the flap 21^x to straighten, constituting automatic means for closing the entrance opening to the powder pocket.

In Figs. 3 to 7 there is illustrated a somewhat simpler embodiment, such embodiment comprising the rear or back blank 3^x which may be identical with the blank 3^x above described, having the like end portions 3^a and 3^b united at the fold line 10 and having the curved ends 3^m . The palm blank 1^x is furnished with the fold lines 33 and 34 ; the liner blank 2^x has the fold lines 30 , 31 and 32 ; and the closure blank 16^x has the fold lines 35 and 36 . When assembled (Fig. 3) the blank 3^x is doubled in the same way as the blank above described, so as to provide a fold to form the free edge 7 of the back member 3 of the mitt. The blank 1^x is assembled with the closure blank 16^x and united by a seam K (Fig. 3). The parts are folded along the lines 34 and 36 and then secured together by a seam at P to form the hem or shutter 22^x . The free edge portion of the blank 16^x lies at the inner side of the member 1^x to form the valve flap V which

terminates at the point 20^z. The liner blank 2^z is folded along the lines 30, 31 and 32 and its several folds permanently united by seams thereby providing the shutter 24^z and the valve flap V¹, the latter being disposed at the inner side of the liner and terminating at the point 21^z, the valve flaps V and V¹ being within the powder pocket 4. Snap fastener elements F and F' are secured to the shutter portion 22^z and to the wrist portion of the liner 2^z respectively, it being sufficient to provide one such fastener substantially midway between the lateral edges of the mitt. In this construction there is no inner valve such as provided by the parts 20^x and 21^x of the previously described embodiment, but the valve flaps V and V¹, which normally lie substantially in contact, tend, when the mitt is inverted, to crumple and block any outward passage of powder between them. At the same time the shutter 22^z, which overhangs the upper margin of the liner, further acts to insure against accidental leakage of powder from the mitt. Obviously, stiffeners, such as the member S may be inserted in the shutter hems 22^z and 24^z if desired.

While certain desirable embodiments of the invention have been illustrated by way of example, it is to be understood that the invention is not necessarily limited to the precise details here illustrated but is to be regarded as broadly inclusive of any and all embodiments and variations of structure which fall within the terms of the appended claims.

I claim:

1. A refillable powder-dispensing mitt of the kind which includes three registering layers of flexible material, one of said layers being a palm member of powder-pervious material and whose shape and area approximate those of the hand upon which the mitt is worn, the second layer being a powder-impervious liner, and the third layer constituting the back of the mitt, stitches permanently uniting said layers along the lateral edges of the mitt and about the fingertip portion of the mitt but leaving the several layers free at the wrist portion thereby defining a powder-receiving pocket and a hand-receiving pocket, and closure means for the powder-receiving pocket located within the wrist portion of the mitt, characterized in that the palm member and liner are provided respectively with elements defining a transversely tapering filling funnel whose inner, smaller end is disposed within the powder pocket, the closure means comprising overlapping shutters secured to the wrist ends of the palm and liner members respectively, and which normally close the larger end of the funnel, the shutter which is secured to the wrist end of the palm member defining one wall of a transverse channel in which the other shutter is normally disposed.

2. A refillable powder-dispensing mitt of the kind which includes three registering layers of flexible material, one of said layers being a palm member of powder-pervious material and whose shape and area approximate those of the hand upon which the mitt is worn, the second layer being a powder-impervious liner and the third layer constituting the back of the mitt, stitches permanently uniting said layers along the lateral edges of the mitt and about the fingertip portion of the mitt but leaving the several layers free at the wrist portion thereby defining a powder-receiving pocket and a hand-receiving pocket, and closure means for the powder-receiving pocket located within the wrist portion of the mitt, characterized in that the wrist end of the liner is defined by a fold forming one longitudinal edge of a hem whose opposite edge is disposed within the entrance to the powder pocket, the

mitt characterized in that flaps of flexible material are secured to the wrist end of the palm and to the wrist end of the lining, respectively, said flaps extending from said wrist ends toward the finger tip end of the mitt and into the powder-receiving pocket and normally being substantially parallel and in contact, the inner edges of said flaps being free, and in having shutter elements constituting additional closure means for the pocket.

3. A refillable powder-dispensing mitt of the kind which includes three registering layers of flexible material, one of said layers being a palm member of powder-pervious material and whose shape and area approximate those of the hand upon which the mitt is worn, the second layer being a powder-impervious liner and the third layer constituting the back of the mitt, stitches permanently uniting said layers along the lateral edges of the mitt and about the fingertip portion of the mitt but leaving the several layers free at the wrist portion thereby defining a powder-receiving pocket and a hand-receiving pocket, and closure means for the powder-receiving pocket located within the wrist portion of the mitt, characterized in that a flap of flexible material depends from the wrist end of the palm member and from the wrist end of the liner respectively into the powder pocket, said flaps being normally substantially parallel, lines of stitches extending inwardly from the wrist end of the mitt and uniting said flexible flaps along inwardly converging lines thereby to define a filling funnel open at its inner end, and normally overlapping relatively stiff shutters closing the larger end of said funnel.

4. A refillable powder-dispensing mitt of the kind which includes three registering layers of flexible material, one of said layers being a palm member of powder-pervious material and whose shape and area approximate those of the hand upon which the mitt is worn, the second layer being a powder-impervious liner and the third layer constituting the back of the mitt, stitches permanently uniting said layers along the lateral edges of the mitt and about the fingertip portion of the mitt but leaving the several layers free at the wrist portion thereby defining a powder-receiving pocket and a hand-receiving pocket, and closure means for the powder-receiving pocket located within the wrist portion of the mitt, characterized in that the closure means includes stiffly resilient but separable normally overlapping parts which by their inherent resiliency tend to remain in pocket-closing position.

5. A refillable powder-dispensing mitt of the kind which includes three registering layers of flexible material, one of said layers being a palm member of powder-pervious material and whose shape and area approximate those of the hand upon which the mitt is worn, the second layer being a powder-impervious liner and the third layer constituting the back of the mitt, stitches permanently uniting said layers along the lateral edges of the mitt and about the fingertip portion of the mitt but leaving the several layers free at the wrist portion thereby defining a powder-receiving pocket and a hand-receiving pocket, and closure means for the powder-receiving pocket located within the wrist portion of the mitt, characterized in that the wrist end of the liner is defined by a fold forming one longitudinal edge of a hem whose opposite edge is disposed within the entrance to the powder pocket, the

ter normally disposed within the hand-receiving pocket and overlapping the fold of the liner, and means releasably securing the shutter to the liner.

6. A refillable powder-dispensing mitt of the kind which includes three registering layers of flexible material, one of said layers being a palm member of powder-pervious material and whose shape and area approximate those of the hand upon which the mitt is worn, the second layer being a powder-impervious liner and the third layer constituting the back of the mitt, stitches permanently uniting said layers along the lateral edges of the mitt and about the fingertip portion of the mitt but leaving the several layers free at the wrist portion thereby defining a powder-receiving pocket and a hand-receiving pocket, and closure means for the powder-receiving pocket located within the wrist portion of the mitt, characterized in that the liner has an extension folded and stitched to provide a two ply hem extending from the wrist end of the liner toward the finger tip end of the mitt, said extension continuing on beyond the hem into the powder pocket to form a flexible valve flap of substantially greater depth than the hem and which is normally substantially parallel to the liner, and in having a second flexible valve flap also extending into the powder pocket to a point beyond said hem, said second flap being normally substantially parallel to the first flap.

7. A refillable powder-dispensing mitt of the kind which includes three registering layers of flexible material, one of said layers being a palm member of powder-pervious material and whose shape and area approximate those of the hand upon which the mitt is worn, the second layer being a powder-impervious liner and the third layer constituting the back of the mitt, stitches permanently uniting said layers along the lateral edges of the mitt and about the fingertip portion of the mitt but leaving the several layers free at the wrist portion thereby defining a powder-receiving pocket and a hand-receiving pocket, and closure means for the powder-receiving pocket located within the wrist portion of the mitt, the liner having an extension which is folded to provide a hem extending from the wrist end of the liner toward the finger end of the mitt, and a strip of stiffly resilient sheet material disposed within said hem.

8. A refillable powder-dispensing mitt of the kind which includes three registering layers of flexible material, one of said layers being a palm member of powder-pervious material and whose shape and area approximate those of the hand upon which the mitt is worn, the second layer being a powder-impervious liner and the third layer constituting the back of the mitt, stitches permanently uniting said layers along the lateral edges of the mitt and about the fingertip portion of the mitt but leaving the several layers free at the wrist portion thereby defining a powder-receiving pocket and a hand-receiving pocket, and closure means for the powder-receiving pocket located within the wrist portion of the mitt,

the liner having an extension folded to provide a hem extending from the wrist end of the liner downwardly into the entrance to the powder pocket, and means secured to the wrist end of the palm member defining a hem whose wrist end is normally parallel and adjacent to the free edge of the palm member, and a strip of stiffly resilient sheet material disposed in each of said hems.

9. A refillable powder-dispensing mitt of the kind which includes three registering layers of flexible material, one of said layers being a palm member of powder-pervious material and whose shape and area approximate those of the hand upon which the mitt is worn, the second layer being a powder-impervious liner and the third layer constituting the back of the mitt, stitches permanently uniting said layers along the lateral edges of the mitt and about the fingertip portion of the mitt but leaving the several layers free at the wrist portion thereby defining a powder-receiving pocket and a hand-receiving pocket, and closure means for the powder-receiving pocket located within the wrist portion of the mitt, and a piece of flexible material secured to the wrist end of the palm member, said material first extending downwardly into the interior of the mitt, then being folded to provide a hem whose free edge is substantially parallel and adjacent to the wrist end of the palm member and which then extends downwardly into the powder pocket to form a valve flap, and a strip of resilient sheet material disposed within said hem.

10. Method of making a three-ply powder dispensing mitt comprising a palm member, a liner and a back member so associated as to define a powder-receiving pocket and a hand-receiving pocket, said method comprising as steps providing palm, liner and back blanks of flexible material, the back blank being transversely folded substantially midway its length to provide two thicknesses of material integrally joined at the folded line, the blank being so folded as to expose the wrong side of the material, finishing the wrist ends of the palm and liner blanks, disposing the liner and back blanks in registry and stitching them together at the lateral edges of their wrist portions, disposing the united palm and liner blanks between the two thicknesses of the back blank with the fold of the latter embracing the wrist edges of the palm and liner blanks, stitching the margins of the several blanks together from the wrist end of the mitt along each edge to points near the fingertip end of the mitt but leaving the tip ends of the blanks unconnected, pulling the wrist end of the mitt out through the opening thus left at the fingertip end thereby to turn the back blank right side out and dispose its two thicknesses with their wrong sides in contact, pulling the fingertip end of the mitt up through the hand-receiving pocket and out at the wrist end so as to turn the hand-receiving pocket inside out, stitching around the fingertip end of the mitt thereby to complete the union of the several plies, and turning the mitt right side out.

DANIEL TOPJIAN.
